UNITED STATES PATENT OFFICE

JOHN HENRY MORSE, OF SHADY GROVE, KENTUCKY.

DESIGN FOR A KITCHEN-RACK.

SPECIFICATION forming part of Design No. 19,907, dated June 17, 1890.

Application filed March 25, 1890. Serial No. 345,273. Term of patent 3½ years.

To all whom it may concern:

Be it known that I, JOHN HENRY MORSE, a citizen of the United States, residing at Shady Grove, in the county of Crittenden and State 5 of Kentucky, have invented a new and original Design for Kitchen-Racks, of which the following is a specification.

The invention relates to a new and original design for kitchen-racks.

10 The object of the present invention is to provide an attractive rack for kitchen use.

In the drawings, Figure 1 is a perspective view of a kitchen-rack showing my new design. Fig. 2 is a side elevation.

15 The essential feature of my design is the particular form of the rack.

Referring to the accompanying drawings, 1 designates angular supporting or bracket bars, having perforated ends 2 and 3, and 20 provided with a downwardly-inclined portion 4 and an approximately horizontal portion

or arm 5, that connects the inclined portion or arm 4 with the end 3.

6 designates horizontal bars that are secured to the inclined portion 4 of the brackets 1, and are arranged at intervals, and are parallel. The alternate horizontal bars are provided at intervals with hooks 7, and the ends 2 and 3 of the supporting and bracket bars are arranged in the same plane.

Having thus described my invention, what I claim is—

The design for kitchen-racks herein shown and described.

In testimony that I claim the foregoing as 35 my own I have hereto affixed my signature in presence of two witnesses.

JOHN HENRY MORSE.
